(57) **CLAIM**

I claim the ornamental design for a pad with channel, as shown and described.

DESCRIPTION

FIG. 1 is a top, front, right side isometric view of a pad with channel, showing a first embodiment of my new design;

FIG. 2 is a bottom, rear, left side isometric view thereof;

FIG. 3 is a top plan view thereof;

FIG. 4 is a bottom plan view thereof;

FIG. 5 is a right side elevation view with the left side being a mirror image thereof;

FIG. 6 is a front elevation view with the rear being a mirror image thereof;

FIG. 7 is a top, front, right side isometric view of a pad with channel, showing a second embodiment of my new design;

FIG. 8 is a bottom, rear, left side isometric view thereof;

FIG. 9 is a top plan view thereof;

FIG. 10 is a bottom plan view thereof;

FIG. 11 is a right side elevation view with the left side being a mirror image thereof;

FIG. 12 is a front elevation view with the rear being a mirror image thereof;

FIG. 13 is a top, front, right side isometric view of a pad with channel, showing a third embodiment of my new design;

FIG. 14 is a bottom, rear, left side isometric view thereof;

FIG. 15 is a top plan view thereof;

FIG. 16 is a bottom plan view thereof;

FIG. 17 is a right side elevation view with the left side being a mirror image thereof;

FIG. 18 is a front elevation view with the rear being a mirror image thereof;

FIG. 19 is a top, front, right side isometric view of a pad with channel, showing a fourth embodiment of my new design;

FIG. 20 is a bottom, rear, left side isometric view thereof;

FIG. 21 is a top plan view thereof;

FIG. 22 is a bottom plan view thereof;

FIG. 23 is a right side elevation view with the left side being a mirror image thereof; and,

FIG. 24 is a front elevation view with the rear being a mirror image thereof.
